(Cl. 19—3)

This invention relates to the silk reeling and aims to provide a method and a device for regulating the thickness or titer of the thread during the reeling.

A primary object of the invention is to provide control means whereby to reel any desired titer of silk by keeping the thread at the desired thickness with very small differences of titer.

A further object of the invention is to provide a control means governed by very slight differences of pressure of air, as promoted by the slightest differences of titer of the thread, and serving to start feed means for piecing a fresh cocoon filament when the thread becomes too thin.

Other objects and advantages are the provision of an improved automatic feed means for the cocoons, including also an improved reeler's trough.

Still other objects and advantages will be apparent from the following specification with reference to the attached drawings, in which:

Figure 1 is a section of an improved device according to the invention, showing in side elevation one of the improved units of the device;

Fig. 2 is an enlarged side view of fluid pressure control means adapted to be mounted within a casing or housing and employed in regulating the thickness of the thread being reeled;

Fig. 3 is an enlarged side elevation, partly in section, of the casing which encloses the control means and shows the gauging head;

Fig. 4 is a front view of the said gauging head, and

Fig. 5 is a schematic diagram of the regulating means and its operating principles.

The improved cocoon reeling device according to the invention comprises a trough 1 having a substantial width and in which the cocoons 2 to be reeled off are soaked with warm water. In order to avoid the sticky matters dispersed into the water of trough 1 from influencing the cocoons, and further in order to permit of keeping the water at the proper temperature according to the invention, the trough is divided by a partition 3 into a shallow upper part in which the cocoons are placed, as will be seen hereinafter, and in a lower part comprising a pit in which on the reeling side of the device, a heater unit 5 is arranged, which is practically constituted by a steam pipe or a sleeved electric heater. The partition 3 constituting the bottom of the upper part of the trough is provided with a substantially vertical wall 6 projecting into the pit 4 and terminating above the bottom thereof. The partition 3 is solid but is open or perforated at the ends.

Due to this arrangement, the water heated by 5 is circulated as clearly shown by the arrows. In this manner the most part of the suspended matters are deposited at the bottom of pit 4 and do not soil the cocoons.

According to the invention, the cocoons are suspended by the worker on a rotatable inclined conical feed arm 7 which extends over the whole length of the trough 1 and is automatically operated by the regulator of the thread thickness each time the thread does not reach the required titer and until a fresh cocoon filament is pieced. In the example as shown the feed arm 7 is driven by shaft 12, which is driven in its turn by a worm gear in mesh with a worm 8' integral with the driving shaft 8 of piecer 13. Shaft 12 is journalled at its free end 9 in a supporting bearing provided at the end of a bracket 10. Piecer shaft 8, together with adjacent parts, is axially bored, 20 as usual and is driven at intervals by motor 11.

The several cocoon filaments 14 to be united to one thread 15 pass through perforations in the piecer 13 and adjoining parts and the thread just formed slides over a slit in a hollow gauging head 16 from which it is drawn at an angle to grooved pulleys 17 and 18 and from this latter it is led again opposite the slot of head 16 where it crosses in known manner a preceding section of the same thread and then is led to grooved pulley 19 and to the winding reel (not shown). Between head 16 and pulley 19, the thread slides against a feeler arm 20 adapted to stop the unit, including the winding reel, each time a thread breaks. This device, however, which may be of a known type, need not be described.

The automatic control and regulation of the titer of the thread is effected pneumatically by utilising the very slight differences of free section of slit 21 (Fig. 4) of head 16, whenever the threads sliding at their crossing point possess a titer that lies under the lower permitted limit.

With particular reference to Figs. 2, 3 and 5, the head 16 is mounted on and in communication with a casing or housing 16' as for example by use of a header member 40 which is suitably mounted within the casing and which is provided with separated bores 17' and 31', the open end of each of the latter being closed by a plug or other closure means. Bore 17' provided with transverse parts 22', 23' and 24' (see Fig. 2) is connected respectively to conduits 22 and 23 and to one leg 24 of a U-tube 25 mounted within the casing (see Fig. 5). Conduit 23 is connected to a pressure box 34 at the lower end of the casing 16' and the conduit 22 connects the bore 17'

to the head 16. A conventional source (not shown) supplies fluid, such as air, under substantially constant pressure to the box 34. A second pressure box 33, arranged in substantially parallel relation to the box 34, is also connected with a fluid pressure source, such as air, which source may be separate from that supplying the box 34.

Pressure box 33 is connected by a conduit 32 to a port 32' in the bore 31' in the header member 40. Bore 31' is also connected, through a port 29, to the leg 28 of the U-tube 25 which latter is filled to a predetermined height with a liquid, water being suitable for this purpose. Valve mechanism having a plunger 27 adapted to be lifted by a float 26 within the leg 28 of the U-tube will close communication of the bore 31' with the U-tube in accordance with the height of the liquid column in the leg 28 of the tube.

An outlet conduit 35 communicates with port 29 so that when the latter is opened by the valve mechanism, air supplied the bore 31' may escape therefrom and into the conduit 35. Conduit 35 is connected to conventional switch means comprising the diaphragm motor 36 and switch member 37 actuated by the diaphragm motor and adapted to close and open the circuit 38 in which the motor 11 is located. The pressure delivered to the diaphragm 36 will hold the switch means closed during the maintenance thereof. In the absence of pressure, the switch means automatically opens. The structure and operation of the switch means are well known in the art and as the details thereof form no part of the present invention, no further description is given.

As heretofore mentioned, the U tube 25, header member 40 and various conduits are contained within the casing 16'. Conventional support structure, such as that shown in Fig. 2 may be employed for this purpose. The casing 16' may be seated on the pressure box structure which in turn may be seated on the motor 11, the latter being supported by any suitable means (not shown).

In the operation of the described unit, it is to be understood that the filaments from a number of cocoons, as indicated in Fig. 1, are being formed into a thread, and that the filaments of additional cocoons are led over the feed arm 7, the cocoons being floatably and movably supported in the water in the trough. The thread being formed passes over the slit 21 in head 16, and if of desired thickness controls the escape of the air delivered from air box 34, conduits 22 and 23, bore 17', hollow head 16, and past the thread in slit 21. If this escape is normal, as predetermined, the pressure of such air on the water in leg 24 of U-tube 25, passing from bore 17' through passage 24' to the U-tube is sufficient to maintain normal equal levels in legs 24 and 28, and maintain the float 26 in position to hold the outlet 29 closed.

If the thread obstruction of slit 21 is reduced, that is, the thread is not of the desired thickness, the escape of air increases, reducing the pressure on the water in leg 24, the level of which rises while the level of the water in leg 28 falls. This lowers float 26, permitting the valve plunger to fall and open the port 29. Air under the desired pressure is then delivered from air box 33, through conduit 32, bore 31' and through conduit 35, to close circuit 38 and energize motor 11. The feed arm 7 is operated to feed the supported cocoons to the piecer 13 for addition of their filaments to the thread being formed, until

the thickness of that thread in passing slit 21 restores normal pressure control, balances the water levels in legs 24 and 28, and in so doing raises float 26 and closes outlet 29 to stop the motor.

It has been found in practice that the above device permits the thickness of the silk threads to be held within desired narrow limits in a manner which is substantially impossible for a skilled worker to duplicate.

In order to keep slit 21 clean, i. e. free from the sticky substances adhering to the wet cocoon thread, this latter is given an oscillating movement transversely of the slit so as to constantly sweep off any solid particles sticking near it. This movement is obtained by making pulley 18 and/or pulley 17 oscillatable to and fro in axial direction. By this means the section of the slit remains substantially unobstructed.

The device permits of automatically regulating the thickness or titer of the threads at will by acting either on the sensitivity of the relay, or by varying the width of slit 21 e. g. by means of a pair of parallel plates 39 which may be drawn together or spread apart, or also by varying the pressure of the air passing through slit 21. However, in the embodiment as shown, the regulation of the titer is effected preferably by varying the height of the liquid column within U-tube 25, the thickness of the thread being inversely proportional to this height.

In practice a number of units like that shown in Figure 1 are arranged side by side, so that the air duct 34 for the low pressure air, as well as the duct 33, (in case a source of higher pressure air is provided, controlled by the low-pressure operated relay), may be cast in a single block 35 and be connected each to a single air source, thus acting as distributing mains for a number of conduits 23-22 on the low pressure side and 32 on the high pressure side.

Of course, the construction features of the device according to the invention may vary within very wide limits. Thus the arrangement of the thread-guiding pulleys and of the head 16 may vary in some particular cases. Head 16 may be arranged in some other position and the relay may be of any other type, provided it be sufficiently sensitive to very slight changes of low pressure air. Instead of a positive pressure inside of the head 16 and conduit 22, a negative pressure, i. e. a slight vacuum, may be employed. The motor 11 may be also a turbine, the float 26 may act on electric contacts, instead of pushing a movable member 27. Also other variations may be employed without departing from the basic principle of the invention.

I claim:

1. A silk reeling machine of the type having means for winding thread composed of a predetermined number of cocoon filaments and comprising feed means on which the ends of filaments from fresh cocoons are attached for feeding to the thread being reeled to replenish the filaments of said thread, a mechanical piecer near the feed means for engaging a filament fed by said feed means and piecing said filament to the thread being reeled, operating means for simultaneously driving said piecer and said feed means, fluid pressure responsive means for causing the operation of starting and stopping mechanism adapted to start and stop said operating means for the piecer and the feed means, a source of fluid under pressure operatively connected to said fluid pressure responsive means, and means

interposed in the flow of said fluid between said pressure source and said pressure responsive means for varying the intensity of the fluid pressure transmitted to said pressure responsive means in accordance with the titer of the thread reeled from the piecer whereby said piecer and feed means are simultaneously driven during periods when the titer of the thread is less than a predetermined minimum value.

2. In a silk reeling machine of the type wherein a thread composed of a predetermined number of cocoon filaments is wound upon a reel, the combination comprising feed means for feeding filaments from a supply of fresh cocoons to the thread as it is being reeled to replenish filaments in said thread, a mechanical piecer positioned to engage a filament fed by said feed means and to piece the filament to said thread, operating means for simultaneously driving said piecer and said feed means, resistant movable means carried by the machine, a source of fluid pressure for transmitting pressure to said resistant movable means, means actuated in accordance with the titer of the thread being reeled from said piecer for varying the intensity of the pressure transmitted to said resistant movable means, a second source of fluid pressure tending to constantly exert a force on pressure actuated starting and stopping mechanism adapted to start and stop the operating means for the feed means and the piecer, valve means for regulating the transmission of fluid from said second source of fluid pressure to said starting and stopping mechanism and an actuating member supported by said resistant movable means for movement therewith, said actuating member being in operative contact with said valve means whereby to effect the opening and closing of the valve means in accordance with the movement of said actuating member.

3. In a silk reeling machine having means for reeling a thread composed of a predetermined number of filaments, each filament being unwound from a separate cocoon, feed means on which the ends of filaments from fresh cocoons are attached whereby to feed said last-named filaments to said thread as it is being reeled to replenish the filaments in the thread, a mechanical filament piecer near the cocoon filament feeding means for engaging a filament fed by said feed means and piecing the filament to said thread, and operating means for simultaneously driving said piecer and said feed means, the combination of a head provided with a slit, said head positioned adjacent the thread being reeled with the thread moving over and partially closing the slit, a source of fluid under pressure, pressure actuated means adapted to regulate starting and stopping means for starting and stopping said operating means for the piecer and the feed means, and means for conducting said fluid into

5 said head and through said slit and to said pressure actuated means, the titer of the thread moving over said slit determining the intensity of the fluid pressure transmitted to said pressure actuated means for effecting the regulation thereof and the operation of the starting and stopping means associated therewith.

4. Feed means for feeding cocoon filaments to a mechanical piecer for a silk reeling device having means for driving the piecer, said feed means comprising a conical shaped member, means for rotatably supporting said conical member at an angle to the horizontal, said conical member having the ends of fresh cocoon filaments attached thereto and moving said filaments towards said piecer, and means connecting the rotatable support means for the conical member to said drive means for the piecer whereby the piecer and the conical member are simultaneously operated.

5. In a silk reeling device for reeling a thread formed of a predetermined number of cocoon filaments, pneumatic means for gauging the diameter of the thread being reeled, means controlled by said pneumatic means for replenishing said thread with a fresh filament from a supply of fresh cocoons when the diameter of the thread being reeled becomes less than the diameter of a thread formed of said predetermined number of filaments due to breakage or exhaustion of a filament forming the desired thread, said pneumatic means having a head provided with a slit therein over which the thread being reeled is drawn, the size of said slit as determined by the 30 diameter of the thread being reeled over it controlling the operation of said replenishing means.

6. In a silk reeling device for reeling a thread formed of a predetermined number of cocoon filaments, pneumatic means for gauging the diameter of the thread being reeled, means controlled by said pneumatic means for replenishing said thread with a fresh filament from a supply of fresh cocoons when the diameter of the thread being reeled becomes less than the diameter of a thread formed of said predetermined number of filaments due to breakage or exhaustion of a filament forming the desired thread, said replenishing means including means for feeding said fresh filaments to said thread comprising a rotatably supported conical shaped member the axis of which is inclined to the horizontal, a liquid containing trough located under said conical member, said fresh cocoons being floated in said trough, the ends of the filaments of said fresh cocoons being connected to said conical member and the filaments being moved towards said thread on rotation of the conical member, and means rotating said conical member on the actuation of said replenishing means.

ANTONIO TASSO.
